J. F. PETRITSCH

AUXILIARY PISTOL STOCK

Filed March 30, 1923

FIG. 1

FIG. 2.

Inventor:

J. F. PETRITSCH,

By *W. T. Fitzgerald & Co.*

Attorney.

UNITED STATES PATENT OFFICE.

JOHN F. PETRITSCH, OF RENO, NEVADA.

AUXILIARY PISTOL STOCK.

Application filed March 30, 1923. Serial No. 628,757.

To all whom it may concern:

Be it known that I, JOHN F. PETRITSCH, a citizen of the United States, residing at Reno, in the county of Washoe and State of Nevada, have invented certain new and useful Improvements in Auxiliary Pistol Stocks; and I do hereby declare the following to be a full, clear, and exact description of the invention, such as will enable others skilled in the art to which it appertains to make and use the same.

The present invention relates to an auxiliary pistol stock, and aims to provide a novel and improved stock adapted for attachment to a pistol which will enable the firearm to be used as a rifle.

Another object of the invention is the provision of an auxiliary pistol stock of novel and improved construction, and capable of being conveniently fashioned from metal, such as a bar or strip of metal.

A further object is the provision of such an auxiliary stock provided with novel means for attaching it to a pistol, whereby the stock can be conveniently attached to and detached from the pistol without prohibitive alterations or trouble.

It is also an object of the invention to provide such an auxiliary pistol stock which is simple and inexpensive in construction, as well as being efficient and practical in use.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a side elevation of the stock as applied to a pistol.

Fig. 2 is a side elevation of the stock removed from the pistol.

Fig. 3 is an enlarged sectional detail on the line 3—3 of Fig. 1.

Fig. 4 is an enlarged plan view of the lower attaching or handle-engaging portion of the stock.

The stock, as shown, is intended for attachment to a Luger pistol, although it can be adapted for other pistols also.

The stock is formed from a single length of a bar or strip of metal which is stiff although resilient, so as to withstand the strains when discharging the pistol, although capable of being sprung for applying the stock to and removing it from the pistol. The bar or strip is bent or formed to provide the upper and lower longitudinal members 10 and 11 connected at their rear ends by the curved shoulder-engaging portion or rest 12 to bear against the shoulder, in the manner of a rifle, for steadyng the pistol when aiming and firing. The bar or strip is also bent to form the secondary upper and lower members 14 and 15 extending rearwardly from the forward ends of the members 10 and 11 at the adjacent sides thereof and connected at their rear ends by a loop or yoke 16 between the ends of the members 10 and 11. The members 14 and 15 are shorter than the members 10 and 11, and the member 14 is disposed against the forward portion of the member 10 at the lower surface thereof, while the member 15 is disposed on the upper surface of the member 11 at the forward portion of said member 11. The upper member 10 has its rear portion offset upwardly, as at 13, whereby the rear portion of the stock is wider than the forward portion thereof.

The terminals of the bar or strip are located at the forward ends of the members 10 and 14, and said terminals are formed into a hook 17, the terminals of the bar or strip being preferably welded or merged together to form the hook, and the members 10 and 14 are also secured together adjacent to the hook by means of a rivet 18 or other securing element. The hook 17 is shaped to engage over and within a loop or eye 19 at the rear end of the pistol 20. The hook 17 can be formed to engage different portions of different makes of pistols, as will be apparent.

The forward end of the stock also has a lower attaching portion to engage the pistol below the upper attaching portion or

hook 17. Thus, the forward ends of the members 11 and 15 are connected by a loop or attaching portion 22 extending upwardly at an obtuse angle, and comprising the front and rear portions 23 and 24 integral with the respective members 11 and 15. The members 11 and 15 are secured together in rear of the loop 22 by means of a rivet 25 or other securing element. The portions 23 and 24 of the loop 22 have a slot 26 extending across or through the bend of the loop, and the slot is narrower in the portion 23 at a distance below the bend of the loop, as at 27, thereby forming the opposite lips or flanges 28 extending toward one another, whereby the loop 22 can be slipped into engagement with the handle 29 of the pistol, said handle being provided along its rear edge with the outstanding lug or tongue 30 of T-shaped cross section. The slot 26 is sufficiently wide to accommodate the web of the lug 30 with the portion 23 in front of the flanges of said lug and the portion 24 in rear of said lug, and the lips or flanges 28 are adapted to engage in front of the flanges of said lug, as seen in Fig. 3. The loop 22 is engaged with the handle 29 by sliding the loop upwardly along the flanges or edges of the lug 30 so that the lips 28 engage in the grooves formed by the flanges of the lug 30. The loop 22 is curved slightly according to the curvature of the lug or portion 30 of the pistol handle.

When the members 10, 11, 14 and 15 are released they will spring apart owing to the resiliency thereof, as seen in Fig. 2, which will also separate the attaching portions at the forward end of the stock. Means is provided for drawing or moving the upper and lower members of the stock toward one another in advance of the loop or yoke 16. Such means includes screws 31, preferably eye screws, having their shanks engaging through the members 10 and 14, and 11 and 15, respectively, and a turn-buckle 32 is threaded on the adjacent terminals of said screws, whereby the upper and lower members can be drawn toward one another. Washers 33 are preferably provided on the screws.

In applying the stock to the pistol, the screws 31 and turn-buckle 32 are unscrewed so that the forward portion of the stock opens slightly, as seen in Fig. 2, and the loop 22 is then slid into engagement with the lug 30 of the handle 29. The hook 17 is then engaged over the loop or portion 19 at the rear end of the pistol. The screws 31 and turn-buckle 32 are then tightened, as seen in Fig. 1, whereby the members 10 and 11 are brought into contact with the members 14 and 15, and if the screws and turn-buckle are tightened sufficiently said members will be sprung toward one another, as seen in Fig. 1, thereby holding the hook 17

and loop 22 in engagement with the pistol under spring pressure. The loop or yoke 16 is resilient to permit the forward terminal portions of the stock to be sprung toward one another, but the loop or bend 16 is sufficiently rigid to prevent the stock from collapsing, as well as preventing the rear portions of the members 10 and 11 from being sprung toward one another excessively. The loop or yoke 16 thus forms a brace between the upper and lower members in rear of the contracting means to make the stock more substantial.

When the stock is thus applied, the pistol can be used in the manner of a rifle, and the stock is light in weight so that the pistol-rifle can be conveniently manipulated. The stock is quickly detached by unscrewing the screws 31 and turn-buckle 32, so that the hook 17 can be disengaged from the pistol, thereby permitting the loop 22 to be slid from the handle.

Having thus described the invention, what is claimed as new is:—

1. A pistol stock having a slotted loop to slidably engage a T-shaped lug on a handle of a pistol, and other means for attaching the stock to the pistol.

2. A pistol stock having upper and lower members, the lower member having a loop provided with a slot to receive a portion of a handle of a pistol and lips to engage said portion for holding the loop assembled with the handle, and the upper member having a portion to engage over a portion of the pistol.

3. A pistol stock comprising upper and lower members, a shoulder-engaging portion connecting the rear ends thereof, secondary upper and lower members secured to and adapted to bear against the aforesaid upper and lower members, respectively, near the forward ends thereof, a resilient loop connecting the secondary members between the ends of the first named members, said members having portions at their forward ends to engage a pistol, and means between said loop and forward ends of the secondary members for springing the first named and secondary members between said loop and the forward ends of said members.

4. A pistol stock comprising upper and lower members, a shoulder-engaging portion connecting the rear ends thereof, secondary upper and lower members secured to and adapted to bear against the aforesaid upper and lower members, respectively, near the forward ends thereof, a resilient loop connecting the rear ends of the secondary members between the ends of the first named members, a loop connecting the forward end of one of the first named members and the forward end of the corresponding secondary member and formed to engage a portion of a pistol, said members and loops

constituting a strip of material with its terminals at the forward ends of the other first named and secondary members, one terminal of the strip being formed with means to engage the pistol, and means for springing said members between the resili-
ent loop and forward ends of said members.

In testimony whereof I have signed my name to this specification in the presence of two subscribing witnesses.

JOHN F. PETRITSCH.
